UNITED STATES PATENT OFFICE.

OTTO WALKER, OF ZURICH, SWITZERLAND.

INHALING APPARATUS.

1,062,750.

Specification of Letters Patent. Patented May 27, 1913.

Application filed March 30, 1912. Serial No. 687,336.

To all whom it may concern:

Be it known that I, OTTO WALKER, a citizen of the Swiss Confederation, residing at Zurich, Switzerland, have invented new and 5 useful Inhaling Apparatus, of which the following is a specification.

My invention has for its object to provide an inhaling apparatus for the uniform generation of vapors for inhaling from a mixture of different liquids.

Vaporization of liquid mixtures, containing liquids of various densities, is generally irregular owing to the difference in the boiling points of the constituents, and consequently, the person inhaling same cannot obtain the real benefit of the properly mixed vapors but only the vapors successively, according to their density. In order to insure uniform vaporizing of such mixtures, a 10 vaporizer is provided in which the liquid-container is fitted with a U-shaped tube ending with an easy incline disposed approximately within the limits of the highest and lowest liquid level of said container and 15 subjected to a heater in such a manner as to vaporize only about the uppermost portion of liquid in the inclined portion of said tube. As the tube is comparatively narrow, the heat will cause the uniform evaporation of 20 the mixed liquid and prevent the vapors from splitting up before issuing from the nozzle end of said tube ready for immediate inhalation.

The annexed drawings illustrate an embodiment of the apparatus according to my invention, and the following is a short description of the figures shown therein.

Figure 1, is a vertical longitudinal section; Fig. 2, is a corresponding elevation 40 with a portion of the front torn away from the casing; Fig. 3, is a cross-section of Fig. 1; and Fig. 4, is a horizontal section on the line A—B of Fig. 2.

The same reference characters denote the 45 same parts throughout all the figures.

In a casing *b*, which is removably supported on a double or hollow base *a* and has a cover *c* and hinged front wall *d*, is disposed a vessel *e* adapted to be charged with liquids and fitted with an outlet tube *f*. 50 The vessel *e* is suitably supported and the tube *f* thereof descends through the base plate and is then bent forward and upward, in the form of the letter U, to about the lowest level in the vessel *e*. The continuation of the tube *f* is bent forward at an incline which reaches to about the highest level in the vessel *e*, said inclined portion being lodged within the hood *i* of a flame-protector *g* within which latter a heater, 55 such as *h*, is provided. The free end of the tube *f*, projecting from the hood *i*, is curved upward and ends in a nozzle *j*. The inclined portion of the tube *f* is directly heated by the flame which latter continuously 60 evaporates small quantities of the liquid mixture within a very limited space, so that the vapors cannot disaggregate before inhalation.

The heater is provided with an outer hood *g* having ventilating holes *k* for the escape of smoke from the flame.

For using the apparatus it is necessary to open, or remove, the top-casing *c* and, after filling the vessel *e*, to light the heater *n*. 70 The latter then produces gentle evaporation of the liquid in the tube *f* and drives out the vapors through the nozzle *j*.

I claim:

An inhaling apparatus which comprises 80 in combination with the usual liquid-vessel and heater, a U-shaped tube, an incline at the forward end of said tube above the heater, and an upturned nozzle at the extremity of the tube, as and for the purpose 85 described.

OTTO WALKER.
